UNITED STATES PATENT OFFICE.

HANS JACOB NORBALLE AND JAMES LIDDLE LAWSON, OF HERTFORDSHIRE, ENGLAND.

MULTIPLE-CONTACT ELECTRIC SWITCH.

1,404,884.

Specification of Letters Patent. Patented Jan. 31, 1922.

Application filed March 10, 1920. Serial No. 364,664.

(GRANTED UNDER THE PROVISIONS OF THE ACT OF MARCH 3, 1921, 41 STAT. L., 1313.)

To all whom it may concern:

Be it known that we, HANS JACOB NORBALLE and JAMES LIDDLE LAWSON, subjects of the King of England, and both residing at Hertfordshire, England, have invented certain new and useful Improvements in Multiple-Contact Electric Switches, (for which we have filed an application in England No. 17988, filed the 13th of October, 1913, application accepted October 13th, 1914, patent sealed December 31, 1914,) of which the following is a specification.

According to the present invention in a multiple contact switch having a row of 15 contact-pieces and a contact-bar therefor, each contact-piece is provided with a flat contact-face so directed as, at the moment of contact, to be substantially parallel with the co-operating contact face of the bar and 20 is yieldingly supported to adjust itself to the thrust of the bar; the contact-bar is so guided that one end thereof has a path more or less in the direction of the line of the row of contact-pieces and its other end 25 a path directed transversely to that of the first said end. The first said end may have a straight line path; in the preferred construction one end is pivoted either to a part guided in a straight line path or to a swinging 30 link and the other end is pivotally connected to a swinging link in such a manner as to swing in a path whose direction is transverse to that of the movement of the first said end. The connection between the 35 contact-bar and the means whereby one of its ends is guided more or less in the direction of the line of the row of contact-pieces is preferably a pin-and-inclined-slot connection for the purpose hereinafter referred 40 to. Each contact-piece is preferably so resiliently supported as to be capable both of a pivotal movement and of a bodily displacement to enable it to adjust itself to the movements of the co-operating contact-bar.

45 The object of this construction is to give the bar such a movement that, at the moment of contact with each contact-piece, the contact edge of the bar at that part is parallel with the flat face of the piece, and moves 50 so as to touch the piece over the whole contact area simultaneously, and further, having made such contact, to produce a subsequent rubbing movement between the surfaces.

55 The invention consists in the construction,

arrangement and combination of parts described hereinafter and pointed out in the claims.

One embodiment of the invention and a modification thereof are diagrammatically 60 represented by way of example in the accompanying drawings, in which—

Figure 1 shows in elevation one construction according to the invention comprising a contact-bar and contact-pieces arranged 65 for a motor-starter panel, and

Figure 2 is a perspective view of a contact-piece and its support;

Figure 3 is a view similar to Figure 1 of a modification.

Like reference letters designate like parts throughout the several views.

As seen in Figure 1, E is a contact-bar for use in an automatic motor-starter. The contact-bar is provided with a contact-strip E¹ 75 forming the contact-face, and is pivoted at its lower end at E³ to a bar B, from which two downwardly-directed rods B¹, B² extend through guides C¹, C² mounted on a panel A to give a straight line motion to the 80 bar B. Any convenient mechanism may be used for moving the bar B in a straight line. The contact-bar is thus carried by the bar B and moves with it, but is guided as to its upper end by pivotal engagement with a 85 swinging link L.

The one end of this link L is pivoted at L¹ in the slot E² in the bar E, and the other end is pivoted to the panel A at L², a buffer stop being provided at L³. A number of 90 contact-pieces M are arranged in a row in which each contact-piece is slightly set back laterally relatively to its fellow beneath it. Each contact-piece has a contact-face I, and has that face so directed that it will be parallel to the face of the strip E¹ at the instant of contact. The way which this position is arrived at is shown in Figure 1, where the numerals 1 to 8 upon the lower end of the contact-bar E indicate successive positions 100 of the pivotal centre E³, and dotted lines numbered 1 to 8 show the corresponding positions of the contact-face of the strip E¹; corresponding successive positions of the pivotal centres L¹ are shown and numbered 105 1 to 8 at the upper end of the bar.

Each contact-piece is constructed as shown in Figure 2, where M is a carbon block mounted upon a conducting pin M¹. The upper end of this pin enters an elongated 110

hole M^2 in the carbon block of such a size as to give not only pivotal movement, but sufficient play to permit a small bodily movement of the block M with relation to the pin M^1 . Towards its lower end the pin carries a metal block M^7 on which is supported a two-finger plate-spring M^8 , whose fingers press on the carbon block, one on either side of a central ridge M^9 . The fingers M^8 are so set as to present the face F in the desired direction about the pin M^1 . A split sleeve M^4 upon the pin M^1 is connected by a flexible conductor M^6 to a split pin M^5 held frictionally in a hole in the block M . The screw-thread at M^8 is to receive nuts, not shown, for securing it in position, and for clamping electrical connections to it.

In operation, as the bar B is raised from the position shown in Figure 1, it causes the lower end of the bar E to follow a straight line path, while the upper end swings about the centre L^2 . The slot E^2 permits, however, a certain amount of lost motion, which, when the parts are solenoid-operated is advantageous. When the pin L^1 is struck by the bottom end of the slot E^2 the upper end of the contact-bar E follows a circular path and the whole bar successively takes up positions in which its contact-face occupies the positions shown in dotted lines numbered 1 to 8. The faces F , however, of the blocks M are so set that as each is encountered by the strip E^1 the contact-face of the latter and the contact-face of the block are parallel to one another; contact is thus made simultaneously over the whole area of a face F . When contact has been established in this way the continued movement of the bar E gives rubbing action upon the block, and the latter moreover both yields bodily and receives a small motion of rotation about the end M^2 of its pin.

Fixed metal contact-pieces N , N^1 and N^2 may be provided, if desired, to co-operate with the rear or under face of the contact-bar, that is to say, the face of the contact-strip E^1 turned towards the panel, to provide a short-circuit path of really low resistance to the main resistance from which tappings are taken to the blocks M .

An alternative construction is shown in Figure 3 which differs from that shown in Figure 1, in that the lower end of a contact-bar E^4 corresponding to the bar E does not receive a straight line motion. This bar E^4 is pivotally connected by a pin B^4 movable in a slot B^{10} to a bar B^3 which is itself pivoted at B^7 on the panel A and is the member by which the bar E^4 is operated. The means shown for swinging the bar B^3 comprise a link B^8 that is connected at one end to the core of a solenoid and carries at its other end a pin movable in a slot B^9 in the bar B^3 . At its upper end the pivotal connection of the bar E^4 with the link L is by means of

a plain pivot L^4 instead of a pin-and-slot connection L^1 , E^2 as in Figure 1. The slot B^{10} at the lower end has its direction inclined both to the general direction of the thrust of the contact-pieces M and to the principal direction of movement of the bar E^4 . The purpose of this pin-and-slot arrangement is to avoid binding action upon the bar B^3 at its pivot B^7 as a result of the combined thrust of the contact-pieces M . As the bar B^3 travels upwards the pin B^4 abuts against the lower end of the slot B^{10} , but so soon as the bar B^3 begins to fall, pressure from the blocks M is eased owing to the direction of the slot B^{10} .

It is preferred, where a dash-pot is employed, to provide one as seen at G , but so constructed as to have a release port which comes into action when the bar is just approaching the top of its stroke, so that this portion of its travel, a very small portion, is executed unchecked by any dash-pot action and therefore by a movement somewhat in the nature of a jerk; this facilitates the upward movement in spite of the accumulated pressure of the contact-pieces M . This arrangement of dash-pot may be applied either to the construction seen in Figure 3 or to that seen in Figure 1.

What we claim as our invention and desire to secure by Letters Patent is:—

1. In an electric switch, the combination of a row of spring-controlled contact-pieces having each a flat contact-face, a contact-bar having a contact-face extending lengthwise along itself, and means for guiding said contact-bar so that one end thereof has a path extending in the direction of the line of said row of contact-pieces, the other end thereof has a path whose direction is transverse to that of the first end, and its contact-face is brought into contact in succession with the contact-faces of the contact-pieces, and means supporting said contact-pieces so that their contact-faces when free are each directed to be substantially parallel with the direction which the co-operating portion of the contact-face of the bar has at the moment of contact therewith.

2. In an electric switch, the combination of a row of spring-controlled contact-pieces having each a flat contact-face, a contact-bar having a contact-face extending lengthwise along itself, and means for guiding said contact-bar so that one end thereof follows a path extending in the direction of the line of said row of contact-pieces, the other end thereof swings about a pivot along a path whose direction is transverse to that of the first end, and its contact-face is brought into contact with the contact-faces of the contact-pieces successively, and means supporting said contact-pieces so that their contact-faces when free are each directed to be substantially parallel with the direction which

- the co-operating portion of the contact-face of the bar has at the moment of contact therewith. 3. In an electric switch, the combination 5 of a row of spring-controlled contact-pieces having each a flat contact-face, a contact-bar having a contact-face extending lengthwise along itself, and guiding means for said bar comprising a guide member having one end 10 that is pivoted to one end of said bar and is movable in a path extending in the direction of the line of said row of contact-pieces, and a link that is fixedly pivoted at one end and has its other end pivotally connected to 15 the other end of said bar and movable along a path whose direction is transverse to that of the former end, said guiding means being so arranged that the contact-face of the contact-bar is brought into contact in succession 20 with the contact-faces of the said contact-pieces, and means supporting said contact-pieces so that their contact-faces when free are each directed to be substantially parallel with the direction which the co-operating 25 portion of the contact-face of the bar has at the moment of contact therewith.
4. In an electric switch, the combination 30 of a row of contact-pieces having each a flat contact-face, a contact-bar having a contact-face extending lengthwise along itself, guiding means for said bar comprising a guide member having one end that is pivotally connected by a pin-and-slot connection to one end of said bar and is movable in a path extending in the direction of the line of said contact-pieces, and a link that is fixedly pivoted at one end and has its other end pivotally connected to the other end of said bar and movable along a path whose direction is transverse to that of the former end, the slot of the pin-and-slot connection being directed 35 transversely both to the general direction of the row of contact-pieces and to a direction at right-angles thereto, said guiding means being so arranged that the contact-face of the contact-bar is successively brought into contact with the contact-faces of the said contact-pieces, and means yieldingly supporting said contact-pieces in such manner that their contact-faces when free are each directed to be substantially parallel with the direction which the co-operating portion of the contact-face of the bar has at the moment 40 of contact therewith.
5. In an electric switch, the combination 45 of a row of contact-pieces having each a flat contact-face, a contact-bar having a contact-face extending along itself, means for guiding said bar comprising a guide member that is mounted to swing about a fixed pivot and has one end that is pivoted to one end of said bar and is movable in a path extending in the direction of the line of said row of contact-pieces, and a link that is fixedly pivoted at one end and has its other end pivotally connected to the other end of said bar and movable along a path whose direction is transverse to that of the former end, said 50 guiding means being so arranged that the contact-face of the contact-bar is brought into contact in succession with the contact-faces of the said contact-pieces, and means supporting said contact-pieces in such manner that their contact-faces when free are each directed to be substantially parallel with the direction which the co-operating portion of the contact-face of the bar has at the moment of contact therewith.
6. In an electric switch, the combination 55 of a row of contact-pieces having each a flat contact-face, a contact-bar having a contact-face extending lengthwise along itself, guiding means for said bar comprising a guide member having one end that is pivotally connected by a pin-and-slot connection to one end of said bar and is movable in a path extending in the direction of the line of said contact-pieces, and a link that is fixedly pivoted at one end and has its other end pivotally connected to the other end of said bar and movable along a path whose direction is transverse to that of the former end, the slot of the pin-and-slot connection being directed transversely both to the general direction of the row of contact-pieces and to a direction at right-angles thereto, said guiding means being so arranged that the contact-face of the contact-bar is successively brought into contact with the contact-faces of the said contact-pieces, and means yieldingly supporting said contact-pieces in such manner that their contact-faces when free are each directed to be substantially parallel with the direction which the co-operating portion of the contact-face of the bar has at the moment of contact therewith.
7. In an electric switch, the combination 60 of a row of contact-pieces having each a flat contact-face, a contact-bar having a contact-face extending lengthwise of itself, means for guiding said contact-bar so that one end thereof moves along a path extending in the direction of the line of said row of contact-pieces, the other end thereof moves along a path whose direction is transverse to that of the first end and its contact-face is brought into contact in succession with the contact-faces of the said contact-pieces, and means supporting said contact-pieces each so as to present its contact-face parallel to the co-operating portion of the contact-face of the bar at the moment of contact, and each capable of resiliently opposed pivotal movement and of resiliently opposed bodily displacement. 65
8. In an electric switch, the combination 70 with a base, a row of contact-pieces having each a flat contact-face, means resiliently supporting the contact-pieces on said base, a contact-bar having a contact-face extending lengthwise along itself, and guiding means comprising a guide member having one end pivotally mounted on said base and its other end pivotally connected by a pin-and-inclined-slot connection to one end of said bar, 75

and a link that is pivotally mounted at one end on said base and has its other end pivotally connected to the other end of said bar and movable along a path whose direction is transverse to that of the former end of the bar, said guiding means being so arranged that the contact-face of the contact-bar is brought into contact in succession with the contact-faces of the contact-pieces, which contact-pieces are normally supported by the said supporting means to have their contact-faces each directed to be substantially par-

allel with the direction which the co-operating portion of the contact-face of the bar has at the moment of contact therewith. 15

In testimony whereof we have signed our names to this specification in the presence of two subscribing witnesses.
